[57] **CLAIM**

The ornamental design for a portable radio telephone or the like, substantially as shown and described.

DESCRIPTION

FIG. 1 is a right front elevational perspective view of a portable radio telephone showing my new design, with the case in opened position displaying the interior arrangement;

FIG. 2 is a right front elevational perspective view thereof showing the case in closed position; with the handset and power cord positioned outside of the case.

FIG 1

FIG 2
